UNITED STATES PATENT OFFICE

139,571

DESIGN FOR A CIGAR AND CIGARETTE LIGHTER

William E. Phillips, Los Angeles, Calif.

Application August 23, 1944, Serial No. 114,978

Term of patent 3½ years

(Cl. D48—27)

To all whom it may concern:

Be it known that I, William E. Phillips, a citizen of the United States of America, residing in the city of Los Angeles, county of Los Angeles, State of California, have invented a new, original, and ornamental Design for a Cigar and Cigarette Lighter, of which the following is a specification, reference being had to the accompanying drawing, forming a part thereof.

Fig. 1 is a top plan view of a cigar and cigarette lighter showing my new design.

Fig. 2 is a front elevational view of the lighter, Fig. 3 is an end view of the same,

Fig. 4 is a rear elevational view with the lighter in inoperative position corresponding to Figs. 1 to 3, and

Fig. 5 is a rear elevational view of the lighter in operative position.

I claim:

The ornamental design for a cigar and cigarette lighter, substantially as shown.

WM. E. PHILLIPS.
